US00D868124S

(12) **United States Design Patent** (10) **Patent No.:** **US D868,124 S**
(45) **Date of Patent:** **** Nov. 26, 2019**

(54) **TARGET PROFILE FOR A PHYSICAL VAPOR DEPOSITION CHAMBER TARGET**

(71) Applicant: **APPLIED MATERIALS, INC.**, Santa Clara, CA (US)

(72) Inventors: **Martin Lee Riker**, Milpitas, CA (US); **Fuhong Zhang**, San Jose, CA (US); **Zheng Wang**, Mountain View, CA (US)

(73) Assignee: **APPLIED MATERIALS, INC.**, Santa Clara, CA (US)

(**) Term: **15 Years**

(21) Appl. No.: **29/629,062**

(22) Filed: **Dec. 11, 2017**

(51) **LOC (12) Cl.** **15-09**

(52) **U.S. Cl.**

USPC **D15/144**; D15/150; D15/199; D13/182

(57) **CLAIM**

The ornamental design for a target profile for a physical vapor deposition chamber target, as shown and described.

DESCRIPTION

FIG. 1 is a top perspective view of a target profile for a physical vapor deposition chamber target.

FIG. 2 is a top plan view thereof.

FIG. 3 is a bottom plan view thereof.

FIG. 4 is a right side plan view thereof.

FIG. 5 is a left side plan view thereof.

FIG. 6 is a front view thereof.

FIG. 7 is a back view thereof; and,

FIG. 8 is an enlarged cross sectional view taken along line 8-8 in FIG. 2.

1 Claim, 6 Drawing Sheets
